UNITED STATES PATENT OFFICE.

WALTER BOESCHE, OF PLYMOUTH, PENNSYLVANIA.

AIRCRAFT.

Application filed April 24, 1925. Serial No. 25,497.

To all whom it may concern:

Be it known that I, WALTER BOESCHE, a citizen of Germany, residing at Plymouth, in the county of Luzerne and State of Pennsylvania, have invented certain new and useful Improvements in Aircraft, of which the following is a specification.

The main object of this invention is to provide an improved type of air craft which 10 combines the characteristics of the heavier than air and lighter than air machines and proposes to use an enclosed bag and a plurality of sustaining planes at various positions on the structure to give the same air 15 buoyancy.

The above and other objects will become apparent in the description below, in which characters of reference refer to like-named parts in the drawing.

20 Referring briefly to the drawing, Figure 1 is a top plan view of the air craft.

Figure 2 is a side elevational view of the same.

25 Figure 3 is a cross sectional elevational view taken on line 3-3 of Figure 2.

Referring in detail to the drawing, the numeral 10 indicates the fuselage. This fuselage is longitudinal in outline and is stream-lined thruout its length having a 30 curved nose fore and aft, and its bottom is substantially semi-circular to decrease air resistance of the fuselage to the minimum. The fuselage has planes 13 and 14 extending transversely therefrom at positions intermediate its length, and these planes are 35 retained in their position by spars 15 which extend upwardly and are mounted on the underside of a flat sustaining surface 16 of the bag. This bag is of the same length as the fuselage and has a semi-circular inverted roof 17 whose ends are connected to the flat surface 16 to form a hermetically 40 sealed compartment 18. It is well known that a plane surface in being projected horizontally thru the air and slightly tilted has an oval vacuum pocket formed above the plane surface. This vacuum pocket is of the same shape and volume as the curved roof 17 of the bag, and therefore this vacuum 45 volume is utilized to aid in lifting the air craft. It is to be noted that the bag used in this construction is rigid and non-yieldable. The roof of the bag is formed in an inverted semi-circular outline to decrease 50 the air resistance of the same to the minimum, as is the case with the fuselage, and

at its forward and rear ends, is provided with a rounded nose. At the rear ends of the airship, a plurality of platforms are anchored. These platforms 19 are shown 55 three in number, but may be of any desired number to suit the needs of control capacity of the air craft to which they are attached. The platforms are superposed one over the other, and between them, have vertical steering blades 20 which are fitted on posts 21, the latter being adapted to be rotated in order to move the blades 12. To each of the platforms 19, an elevator aileron 22 is hingedly attached, the hinges forming part 60 of and projecting from the forward edge of the aileron and cooperate with hinge pins anchored in the rear ends of the platforms 18. These ailerons are also superposed one over the other and move in unison by being 65 connected together by pairs of parallel spars 23. The planes 13 and 14 are of hollow construction and house the driving means for propelling shafts 24 which extend from the forward or entering edges of the planes and 70 have propellers 25 mounted at their forward ends. These propeller shafts diverge forwardly toward the outside edge of the planes in which they are anchored so that a side wise and forward thrust is obtained, resulting in increased propelling power. The 75 motive power which is adapted to drive these propeller shafts is housed within the fuselage and is connected to the propeller shafts by gearing and other shafts, as is most 80 convenient. The entire airship is supported on wheels, skids, or any other means required to fit the local conditions of the place at 85 which the airship is used. The wheels 26, shown in several views of the drawing, are 90 of the pneumatic type and are rotatably mounted on a shaft 27 which is supported in the bearings of undercarriage frames 28 and 29, these frames being secured to the floor of the fuselage at convenient spaced-apart positions. The compartment 30 of the 95 fuselage may be so constructed to serve for passengers or freight, or for military use, and is entered thru a door 31 which may be located conveniently at the center of the 100 ship.

The main characteristics of this airship is that it is used as a vacuum pocket formed by the bottom 16 of the bag as it sails thru the air. This vacuum pocket would be of an 110 area enclosed by the outlines of the floor 16 and the roof 17 of the bag, and the bag is

therefore constructed with these dimensions in view. The bag is provided with an inverted semi-circular roof to give the least amount of surface friction and resistance to forward travel and its lower surface is formed flat to provide a sustaining blade for the entire airship. Ascent and descent is controlled by the elevator ailerons 22 and the rudder blades maneuver the ship horizontally. Forward travel of the entire ship may be obtained by rotation of the propeller blades 25 which are actuated from the power situated within the fuselage chamber 30.

15 I claim:—

1. An airship comprising a longitudinal bag having a stream-lined roof, a longitudinal enclosed fuselage suspended beneath the bag, the walls of the fuselage joining the bottom of said bag, planes extending transversely from both sides of said fuselage and propellers projecting forwardly from the planes, and means for controlling the flight of said airship.
2. An airship comprising a stream-lined bag comprising an inverted semi-circular roof, the bottom of said bag being formed into a flat sustaining surface, a fuselage sus-

pended beneath the flat surface of said bag, a plurality of horizontal rudders superimposed one above the other and parallel to each other, and vertical rudders between said rudders for steering the ship horizontally, the rudders being movable to steer the ship angularly.

3. An airship comprising a stream-lined rigid bag having an inverted semi-oval roof, the bottom of said bag being formed into a flat plane sustaining surface, a fuselage suspended beneath the flat surface of said bag and extending its entire length, a plurality of horizontal rudders superimposed one above the other and parallel to each other, and planes extending outwardly from the fuselage and being suspended from the flat surface of the bag intermediate their length, propeller shafts mounted in the planes and projecting forwardly and angularly from the entering edges of said planes in opposite directions, and propellers on the shafts of said planes when rotated being adapted to create a forward and externally sidewise thrust of said airship.

In testimony whereof I affix my signature.

WALTER BOESCHE.
